Geo. P. Kimmel
ATTORNEY.

UNITED STATES PATENT OFFICE.

ELMORE MILOTTE, OF EUREKA, CALIFORNIA, ASSIGNOR OF ONE-HALF TO J. B. MORGANTI, OF EUREKA, CALIFORNIA.

OVERHEAD HAULAGE CARRIER.

Application filed September 14, 1927. Serial No. 219,528.

This invention relates to an overhead haulage carrier, and has for its object to provide, in a manner as hereinafter set forth, a carrier of such class for expeditiously elevating and transporting a load in suspended position from a loading point to a receiving point and for lowering the load for discharge at the receiving point.

A further object of the invention is to provide, in a manner as hereinafter set forth, a carrier for the purpose referred to including a combined haulage and load carrying cable and means for latching said cable to provide for the suspension of the load and for the haulage of the latter by the cable.

Further objects of the invention are to provide an overhead haulage carrier, in a manner as hereinafter set forth, and which is comparatively simple in its construction and arrangement, strong, durable, compact, thoroughly efficient in its use, conveniently operated, and comparatively inexpensive to set up.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a fragmentary view, in side elevation, of an overhead haulage carrier in accordance with this invention.

Figure 2 is a fragmentary view, in longitudinal section, illustrating the carriage and the latching means therefor and further illustrating the latching means and the combined haulage and load carrying cable.

Figure 3 is a section on line 3—3, Figure 2.

Figure 4 is a section on line 4—4, Figure 2.

Figure 5 is a fragmentary view, in front elevation, illustrating one of the latching members for the hauling cable and with said member in latching position.

Figure 6 is a detail, in elevation, illustrating one of the latching members of the haul-

age cable and with said member in non-latching position.

An overhead haulage carrier, in accordance with this invention comprises an inclined track 1, formed from a cable of the desired diameter and which is disposed at an inclination and has its upper end coupled with the standards 2 of appropriate height as at 3. The lower end of the track 1 is anchored in any suitable manner and the anchoring of the lower end of the track 1 is not shown. That side of the standards 2, upon which is arranged the connection 3 for the track 1, has rotatably supported thereon a sheave 4 positioned a substantial distance above the connection 3. On the same side of the standards 2, and below the connection 3, a sheave 5 is rotatably supported from said standards 2, a substantial distance below connection 3.

A combined haulage and load carrying cable is indicated at 6, and which travels over the sheave 5 and said cable 6 winds on and off a drum, not shown. The cable 6 has fixedly secured therewith a pair of stop members 7, 8' arranged a substantial distance from each other.

Travelling on the track 1 is a carriage referred to generally by the reference character 8 and which is formed of a pair of spaced rectangular side plates 9, 10 and a pair of end members 11, 12. Each end member is of less height than the height of the side plates. The end member 11 is formed with a pair of sections arranged in spaced relation to provide that end of the carriage 8, which opposes the standards 2, with an opening 13 of appropriate width. The end members 11, 12 are flush with the bottom edges of the side plates 10, 9, but said members 11, 12 have their upper ends spaced a substantial distance below the top edges of the plates 10, 9, thereby providing the top of each end of the carriage 8 with an opening 14, for the passage of the track 1. Secured to the side members 9, 10 of the carriage 8, are transverse shafts 15, and upon each is rotatably mounted a groove pulley 16 which travels upon the track 1. The pulleys 16 oppose the openings 14, at the ends of the carriage 8, and said pulleys 16 are positioned in close proximity to said openings 14, see Figure 2. Secured to the side plates 9, 10 of the carriage 8, at the lower portion thereof,

is a shaft 17, upon which is revolvably mounted a groove pulley 18 over which travels the haulage cable 6 and the latter extends through the opening 13 passes around the pulley 18 and depends from the bottom of the carriage 8. The bottom of the carriage is open. The shaft 17 is positioned between the vertical median of the carriage 8 and the end member 12, but is nearer the vertical median of the carriage 8 than to the end member 12. Arranged within the carriage 8 and positioned between the pulley 18 and the end member 11, are spaced sets of transversely extending spaced stop bars. One set of stop bars is indicated at 19 and the other set at 20. The cable 6 passes between certain of the stop bars of each set. The stop bars of the set 20 are arranged in proximity to the pulley 18. The stops 7, 8 carried by the cable 6 also pass between certain of the stop bars of each set, see Figure 2.

Connected to the side members 9, 10 of the carriage 8 are transverse shafts 21, 22 arranged in parallel spaced relation and pivotally mounted upon the former is a bell crank 23 and upon the latter is a bell crank 24. The arm 25 of the bell crank 23 is of greater length than the arm 26 of such bell crank and the arm 27 of the bell crank 24 is of greater length than the arm 28 of such bell crank. The arms 25, 27 project a substantial distance above the side plates 9, 10 of the carriage 8, and attached to the upper ends of the arm 25 is a shifting cable 29 therefor and attached to the upper end of the arm 27 is a shifting cable 30 therefor. The cables 29, 30 extend a substantial distance below the carriage 8 so they can be conveniently reached by the operator. The arms 26, 28 are disposed at an inclination and project from the arms 25, 27 respectively towards the end member 11 of the carriage 8 and the said arms 26, 28 are arranged over the sets of stop bars 19, 20 respectively. The arms 25, 27 are the upper arms of the bell cranks 23, 24 respectively and the other arms 26, 28 are the lower arms of the bell cranks 23, 24 respectively. With reference to Figure 5 the lower arm of each bell crank is bifurcated, as indicated at 31, and extending into the furcation is the upper end 32 of a bifurcated latching member and the bifurcation of such member is indicated at 33. The latching member saddles the haulage cable 6. The width of the furcation in the latching member is materially less than the diameter of the stops 7, 8 which are carried by the haulage cable 6. The upper end 32 of the latching member is formed with a transversely extending opening 34 through which extends a pivot pin 35 for connecting the latching member to the lower arm of a bell crank. The latching member which is

is indicated at 36 and the latching member which is carried by the lower arm 28 of the other bell crank is indicated at 37. The upper arms of the bell cranks project at a forward inclination from their lower ends and towards the end member 12 of the carriage 8. The sets of stop bars, in connection with the members 36, 37 and bell cranks 23, 24 provide latching devices for stops of the haulage cable, and the purpose for which the latching devices are intended for will be hereinafter more fully referred to.

Fixedly secured within the carriage 8, and projecting through the opening 13, a substantial distance above the haulage cable 6, is an arm 38, provided with a nose 39, at its outer end. Said arm 38 coacts with a spring controlled latching mechanism for releasably retaining the carriage from movement when the carriage is at the loading point. The latching mechanism comprises a housing 40, which is fixedly secured by the holdfast devices 41, to the track 1, in proximity to the upper end thereof, or above the loading point. The housing 40 depends from the track 1, and has its bottom formed with an opening 42 and one end with an opening 43 through which is adapted to pass the arm 38. Secured at one end, as at 44, to the housing, is a resilient latching member 45, provided at its free end with a nose 46, which coacts with the nose 39 for releasably securing the carriage in a stationary position at the loading point. Arranged within the housing 40 and interposed between the top thereof and the latching member 45, is a controlling spring 47 for said member 45. Connected to the bottom of the member 45, and extending through the opening 42, and further depending a substantial distance below the housing 40 is a yoke 48, through which passes the haulage cable 6. The yoke 48 is pivotally connected as at 49, and has an angle shaped upper end 50 which provides means for shifting the member 45, clear of the nose 39, when the yoke is moved to the dotted line position as shown in Figure 2. A shifting cable 51 is provided for the yoke 48 and is of a length to be conveniently reached by the operator. The carriage when moved upwardly upon the track 1, is automatically coupled with the latching member 45, as the arm 38 moves into the housing 40 through the opening 43 and rides against the nose 46 and after the nose 39 clears the nose 46, the action of the spring 47 will provide for the nose 46, opposing the nose 39, whereby the carriage 8 will be latched from downward movement upon the track 1.

Connected to the carriage 8 is a pulling cable 52 therefor, which travels over a pair of sheaves 53, supported in any suitable manner at a desired distance from the standards 2. The cable 52 also travels over the sheave 4 and winds and unwinds on the

drum not shown. The purpose of the pulling cable 52 is to shift the carriage 8 from its upper position to its lower position with respect to the track 1, or in other words, for moving the carriage from a non-loading point to the loading point. In Figure 1 the dotted line showing with respect to the carriage 8 and haulage 6 is the loading point and the full line showing is the unloading point.

Figure 1 illustrates the carriage 8 in two positions and the load X in four positions, and the positions of the load are indicated at A, B, C and D. Secured to the housing 40 is an arm having a portion 54 thereof extending above and in parallel relation to the track 1. Depending from the lower face of the portion 54 is a pair of stops 55, which are disposed at the same angle as the arms 25 and 27 of the bell cranks 23 and 24, and are spaced the same distance apart as said arms 25 and 27.

In the operation of my device, the carriage 8 is moved by means of the cable 52 to the position shown in dotted lines in Figure 1. The cable 6 is then positioned to have one end thereof secured to the load X as indicated at position A in Figure 1. In this position the stop 8' will be located between the load X and the carriage 8 and the stop 7 will be located between the latch members 36 and 37 of the carriage 8. To lift the load, the carriage 8 is held in the position shown in dotted lines by the cable 52 and power is applied to the cable 6. The latch member 36 is raised by means of the cable 29 which is secured to the arm 25 of the bell crank 23 to permit the stop 7 to pass said latch member. After the stop 7 has passed the latch member 36, the cable 29 is released, thereby permitting the latch member 36 to fall by gravity into its normal position with its bifurcated end straddling the cable 6. When the load X has been raised to the position shown at position B in Figure 1, the stop 8' will have passed into the carriage 8 to a position between the latch members 36 and 37. The stop 8' moves into this position by bearing on the face of the latch member 37, thereby causing said latch member to swing on its pivot 35. As soon as the stop 8' has cleared the bifurcated end of the latch member 37, said latch member is permitted to fall by gravity into normal position with its bifurcated end straddling the cable 6.

At this point, the pressure exerted on the carriage 8 by the cable 52 is released, and a continuous pull on the cable 6 causes the carriage 8 to move along the track 1 towards the housing 40. The power is transmitted from the cable 6 to the carriage 8 to move the latter, due to the contact of the stop 8' with the latch member 36. The latch member 36 is prevented from swinging about its

pivot 35 by the stops 19 which are disposed transversely of the carriage 8.

When the carriage 8 reaches the position shown in full lines in Figure 1, the nose 39 of the arm 38 will have moved through the opening 43 in the housing 40 into engagement with the nose 46 of the latching member 45 secured within the housing 40.

Simultaneously with the latching of the arms 38 and 45, the upper ends of the arms 25 and 27 of the bell cranks 23 and 24 will have moved into forcible contact with the stops 55 depending from the arm portion 54 which is carried by the housing 40.

The bell cranks are actuated by this contact, causing the latch members 36 and 37 to be moved vertically to the position shown in full lines in Figure 2. In this manner, the cable 6 is automatically released relative to the carriage 8, thereby permitting the cable 6 to be drawn through the carriage 8 to lower the load X to the position shown at position D in Figure 1.

In this position, both the stops 7 and 8' are positioned between the load and the carriage 8. When it is desired to return the carriage to loading position, the cable 6 is drawn through the carriage 8

for a proper distance to locate the stop 7 between the latch members 36 and 37. The carriage 8 may then be returned to loading position by means of the cable 52, after releasing the arms 38 and 45 from engagement by means of the cable 51 and yoke 48.

When the carriage 8 starts to move along the track 1 towards the loading position, the arms 25 and 27 of the bell cranks 23 and 24 are immediately released from contact with the stops 55, thereby permitting the latch members 36 and 37 to fall by gravity into their normal positions with their bifurcated ends straddling the cable 6, one of said latch members being disposed on either side of the stop 7.

When the carriage 8 is being returned to loading position, relative movement between the cable 6 and the carriage 8 is prevented by the engagement of the stop 7 with the latch member 36.

It will be noted that the stops 7 and 8' may move into position between the latch members 36 and 37 from either direction, but are prevented from moving out of such position except by actuation of one of the bell cranks.

The lock can be operated by means of a power line attached to the arms of the lock by putting in a spiral spring heavy enough to carry the weight of the power line plus a slight strain and by having it thus the lock can be released any place on the sky line without having to take the carriage to the holder which would be better for some classes of work.

It is thought that the many advantages of an overhead haulage carrier, in accordance with this invention and for the purpose re-

ferred to, can be readily understood, and although the preferred embodiment of the invention is as illustrated and described, yet it is to be understood that changes in the 5 details of construction can be had which will fall within the scope of the invention as claimed.

What I claim is:—

1. An overhead haulage carrier comprising a carriage, a track therefor, a combined haulage and load supporting cable extending into and depending from said carriage, spaced stops secured to said cable, a pair of spaced latching means within said carriage, 10 means to provide for one of said stops to coact with said latching means to maintain the load in a suspended position and for the propelling of the carriage in one direction from said cable, means to provide for 15 the other of said stops to coact with said latching means to maintain the load engaging end of the cable, when free of the load, in an elevated position when the carriage is travelling in an opposite direction, and 20 means for shifting said carriage in said opposite direction.
2. An overhead haulage carrier comprising a carriage, a track therefor, a combined haulage and load supporting cable extending 25 into and depending from said carriage, spaced stops secured to said cable, a pair of spaced latching means within said carriage, means to provide for one of said stops to coact with said latching means to maintain the load in a suspended position and for the propelling of the carriage in one direction from said cable, means to provide for 30 the other of said stops to coact with said latching means to maintain the load engaging end of the cable, when free of the load, in an elevated position when the carriage is 35 travelling in an opposite direction, means for shifting said carriage in said opposite direction, means for automatically latching said carriage stationary when it arrives at a point of discharge for the load, and means for automatically releasing the cable to provide for the lowering of the load when the carriage arrives at the point of discharge for the load.

ing end of the cable, when free of the load, 40 in an elevated position when the carriage is travelling in an opposite direction, means for shifting said carriage in said opposite direction, means for automatically latching said carriage stationary when it arrives at a 45 point of discharge for the load, and means for automatically releasing the cable to provide for the lowering of the load when the carriage arrives at the point of discharge for the load.

3. An overhead haulage carrier comprising a carriage, a track therefor, a combined haulage and load supporting cable extending into and depending from said carriage, spaced stops secured to said cable, a pair of spaced latching means within said carriage, 50 means to provide for one of said stops to coact with said latching means to maintain the load in a suspended position and for the propelling of the carriage in one direction from said cable, means to provide for the other of said stops to coact with said latching means to maintain the load engaging end of the cable, when free of the load, 55 in an elevated position when the carriage is travelling in an opposite direction, means for shifting said carriage in said opposite direction, means for automatically latching said carriage stationary when it arrives at a 60 point of discharge for the load, and means for automatically releasing the cable to provide for the lowering of the load when the carriage arrives at the point of discharge for the load, and means for shifting said latching means clear of said stop.

In testimony whereof I affix my signature hereto.

ELMORE MILOTTE.
